OUTBOARD PROPULSION UNIT

Elmer Carl Kiekhaefer, Winter Haven, Fla., and Daniel F. McCormick, Fond du Lac, Arthur F. Miller, Oshkosh, and Irving W. North, Fond du Lac, Wis., assignors to Kiekhaefer Corporation, Fond du Lac, Wis., a corporation of Delaware

Filed Nov. 13, 1962, Ser. No. 72,465

Term of patent 14 years

(CL. D71—1)

FIGURE 1 is a side elevation of the outboard propulsion unit, showing our new design;

FIGURE 2 is a rear elevation of the propulsion unit; and

FIGURE 3 is a top plan view thereof.

The transom shown in broken lines is included for illustrative purposes only.

The side not shown is a mirror image of the side shown except for the absence from the upper housing of a tilt release lever and the supporting embossment

therefor as will be evident from the showing in FIGS. 2 and 3.

We claim:

The ornamental design for an outboard propulsion unit, substantially as shown and described.
